ATTACHMENT FOR MUSICAL STRING INSTRUMENTS

Thomas F. Goodwin, Muldrow, Okla.

Application October 4, 1943, Serial No. 504,939

4 Claims. (Cl. 84—320)

This invention relates to an attachment for a musical string instrument, and the primary object of the invention is the provision of a device which will permit a person, while playing a musical instrument wherein the hands are fully utilized, to play accompaniments on a string musical instrument, such as a guitar, through the use of a foot movement and the construction of the device is such that it may be easily and quickly applied and removed from the string instrument when desired.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawing, in which

Figure 1 is a side elevation, partly in section, illustrating an attachment applied to a fragmentary portion of a string instrument and constructed in accordance with my invention.

Figure 2 is a top plan view showing the device in applied position on the instrument.

Referring in detail to the drawing, the numeral 5 indicates an elongated supporting element or bar on which are formed oppositely extending supporting members 6 and 7. The supporting members 6 and 7 are located substantially intermediate the ends of the supporting element or bar 5 and one of the supporting members has attached thereto a bow shaped attaching element 8 terminating in a clamp 9 including a set screw 10 whereby the supporting element or bar 5 may be mounted on a sound box 10' of a guitar or similar string musical instrument.

By referring to Figure 1 it will be seen that the clamp will permit the mounting of the device on the instrument by applying the clamp to a top wall of the sound box, the usual opening 11 of the sound box permitting the clamp to be easily and quickly applied to said wall.

The attaching element 8 arranges the supporting element 5 above the top wall of the sound box and at a selected inclination relative thereto and locating the member 7 adjacent to and directly over the top wall of the sound box and on which is journaled a gear 12. Mounted on one face of the gear 12 are groups of actuating pins 13 adapted, during the rotation of the gear 12 in a step by step manner, to impart movement to strikers 14 each of elongated formation and constructed of flexible material with one end secured

to a bridge 15 forming a part of the member 6. Each striker has an offset 16 to be engaged by selected pins 13 of the gear 12.

The strikers 14 have their free ends curved, as shown at 17, and disposed adjacent to selected strings of the musical instrument. Therefore, it will be seen that as the gear 12 is rotated in a step by step movement the pins 13 engaging the offsets 16 of the strikers will cause said strikers to be flexed and quickly freed so that they will strike the selected strings of the musical instrument to produce musical tones as an accompaniment to music produced on another musical instrument played by the same person.

15 A rack bar 18 is pivotally and slidably mounted on the element 5, as shown at 19, the latter being provided with a slot 20 to receive the pivot. One end of the rack bar has fastened thereto a flexible operating element 21 operating through a 20 guide eye 22 applied to the lower end of the member 5. The flexible element 21 is adapted to be connected to a foot treadle (not shown). Connected to a pin 23 on the element 5 and to one 25 end of the rack bar 18 is a coil spring 24 acting to normally sustain the rack bar in its uppermost position and disengaged from the teeth of the gear 12, so that when a pull is made on the flexible element 21 in the direction indicated by the arrow in Figure 1, the rack bar 18 is caused to pivot and slide relative to the element 5 becoming engaged with the teeth of the gear 12 and thereby impart movement to said gear. This movement is sufficient to cause a pin to engage an offset 16 of a striker 14 and flex said striker so that on the pin 30 becoming disengaged therefrom rapidly, permits said striker to strike a string of the musical instrument and thereby produce a musical tone. As soon as the pull on the flexible element is released, the spring 24 restores the rack bar 18 to its initial position, as shown in Figure 1, ready to again operate the gear a partial turn by the next pull placed on said flexible element through the movement of the foot of the player.

45 While I have shown and described the preferred embodiment of my invention, it will be understood that minor changes in construction, combination and arrangement of parts may be made without departing from the spirit and scope of the invention as claimed.

50 Having thus described the invention, what I claim is:

1. In an attachment for a string musical instrument, a supporting bar, means for securing said bar to a sound box of a string instrument, spring fingers constituting flexible strikers car-

ried by said bar and normally spaced a limited distance from strings of the instrument, a rotatable member carried by the bar, pins on the rotatable member engageable with the strikers to flex the latter, and manually operated means for operating said rotatable member to bring about striking action of the strikers on the strings.

2. In an attachment for a string musical instrument, a supporting bar, a clamp for detachably securing said bar to a sound box of a string instrument, spring fingers constituting flexible strikers carried by said bar and normally spaced a limited distance from the strings of the instrument and each provided with an offset, a rotatable element mounted on said bar and including spaced pins adapted to engage and disengage the offsets of the strikers upon rotation of said rotatable element and thereby flex the strikers to cause rapid engagement and disengagement with the strings to create musical tones and manually operated means for operating said rotatable element to effect a step by step rotation of said rotatable member.

3. In an attachment for string musical instruments, a supporting bar, means for detachably mounting said bar on a sound box of a string instrument, spring fingers constituting flexible strikers mounted on said bar and normally spaced a limited distance from strings of the instrument, a gear journaled on said bar and including pins, said strikers having offsets to be engaged and disengaged by the pins during the

rotation of the gear in a step by step movement for flexing the strikers to bring about rapid engagement and disengagement thereof with the strings to produce musical tones, and a rack bar movably mounted on the supporting member and adapted to engage and disengage the gear for the rotation thereof in a step by step movement, and manually operated means for effecting movement of the rack bar.

- 10 4. In an attachment for string musical instruments, a supporting bar, means for detachably mounting said bar on a sound box of a string instrument, spring fingers constituting flexible striking elements mounted on said bar and normally spaced a limited distance from strings of the instrument, a gear journaled on said bar and including pins, said striking elements having offsets to be engaged and disengaged by the pins during the rotation of the gear in a step by step movement for flexing the strikers to bring about rapid engagement and disengagement thereof with the strings to produce musical tones, a rack bar pivotally and slidably mounted on said supporting member, and adapted for movement into 15 position for engaging said gear, a spring connected to the rack bar and to said supporting member for normally sustaining the rack bar disengaged from the gear, and a manually operable flexible element connected to the rack bar 20 for imparting pivotal and sliding movement of the rack bar to effect engagement with the gear and to effect a step by step rotation of the gear.

THOMAS F. GOODWIN.
